UNITED STATES PATENT OFFICE.

FRANKLIN RICE, OF DAYTON, OHIO.

AUTOMATIC SWITCH FOR TRACTION-LINES.

1,085,485.

Specification of Letters Patent.

Patented Jan. 27, 1914.

Application filed April 14, 1909. Serial No. 489,881.

To all whom it may concern:

Be it known that I, FRANKLIN RICE, a citizen of the United States, residing in Dayton, county of Montgomery, State of Ohio, have invented certain new and useful 5 Improvements in Automatic Switches for Traction-Lines, of which the following is a full, clear, and exact description, reference being had to the accompanying drawings, 10 forming part of this specification.

My invention relates to that certain novel construction and arrangement of parts to be hereinafter particularly pointed out and claimed, whereby the shifting of the switch 15 point in the switching of traction cars from one track to another may be performed automatically by the car as it approaches the switch, and under the control of the motorman, without stopping the car.

20 The switch point is shifted by the action of a solenoid directly connected to the switch point, and the current is supplied to the solenoid from contact boxes located a convenient distance from the switch point, 25 with which boxes a contact plate on the car connects, the contact plate, normally disconnected, being so wired that the motorman can switch on the current to actuate the solenoid when contact is made as the switch 30 is approached.

The object of the invention is to provide a simple, cheap and effective construction which can be readily and easily applied to the car and located in the street, and in 35 which the solenoid shall be completely protected from any liability to damage or deterioration from dampness or the accumulation of water.

40 In the drawings Figure 1 is a plan view of a portion of the main line and branch of a traction line with my improved device applied thereto. Fig. 2 is a side elevation of a traction car illustrating the contact devices. Fig. 3 is a central longitudinal section of the operating solenoid and its connections. Fig. 4 is a perspective view of one 45 of the contact boxes. Fig. 5 is a central longitudinal section of same. Fig. 6 is a longitudinal section of the switch under control 50 of the motorman for throwing in the current.

55 1, 1 represents a portion of the main line and 2, 2 a branch line and 3 the ordinary switch point pivoted at 4 on the frog 5. The switch point 3 is provided with a depending lug 6 secured near the outer pointed end

of the switch point, which lug extends through a slot 7 in the supporting base 8 of the frog and down into a box 9. Directly connected to this lug is the rod 10 to which 60 the electromagnetic core 11 of the solenoid is attached.

In order to prevent moisture and water which may accumulate around the solenoid from affecting the windings, the solenoid 65 is constructed as follows: The outer casing is constructed of a metal cylinder 12 with an integral cap or head 13 at one end, and a screw threaded cap 14 at the other. 15 is a metal tube screw threaded into the cap 13, 70 and passing through a smooth opening in the cap 14 lengthwise through the center of the case and in this tube 15 the core 11 slides loosely. 16 and 17 are the two solenoid coils which are wound in opposite directions and 75 separated by the fiber washer 18, and these coils are then pushed into the case around the tube 15, the cap 14 screwed on and the washer 19 and nut 20 are then secured on the outer end of the tube 15 so that a perfectly tight water-proof casing is provided 80 for the coils. The solenoid is then placed in a box 21, open at its forward end and the box brought up against the side of the frog which holds the switching point, and the 85 connection made as above described, so that as the current is sent through the coils in one direction or the other, the solenoid core is moved to swing the switch point from side to side. The three wires 22 from the 90 solenoid coils pass through a fiber bushing in the end of the box 21. One of the wires is connected with the ground or rails of the track, another wire properly insulated runs to the contact box 26, which is located in the 95 street a proper distance from the switching point so that there will be ample time to throw the switch when the car is moving at a fair rate of speed, and the third wire from the solenoid properly insulated runs 100 to the contact box 27, located on the branch line at such a distance that as soon as the rear wheels have passed the switch point, contact may be made with this box. These contact 105 boxes are illustrated in detail in Figs. 4 and 5. The box is a rectangular metal box 28, of a size about equal to an ordinary paving block, which is secured on the cross tie by the lugs 29, a transverse brace 30 is provided for the interior of the box to which 110 the lid or cover 31 is secured, the lid being thoroughly insulated from the body of the

box by the fiber washer 32. 33 is the single screw for fastening the lid in place, the screw being secured to the transverse cross brace 30, and thoroughly insulated by the 5 fiber bushing 34. The wire from the solenoid passes into the side of the box through the fiber insulator 35, and is connected with the screw 33.

The top surface of the lid is beveled off 10 as shown in Figs. 4 and 5, so that the lid extends above the surface paving only about an inch and one-half and forms no obstruction whatever in the use of the street.

Secured in a convenient position underneath the body of the car, is a metal spring contact plate 36, which extends down nearly to the street surface in a position to come in contact with the lid 31, of the contact box as the car passes on the track. This contact 15 plate is about as wide as the upper surface of the lid, and is of spring metal so that it will readily pass by any obstruction in the street. Connection is made between this contact plate 36, and the bolt 37 mounted in the 20 outer end of the switch lever 38, pivoted on a casting 39 secured underneath the platform of the car, and the contact bolt 40 mounted in the casting 39 is connected by the wire 47 with the line circuit. The bolts 25 37 and 40 are thoroughly insulated by the fiber plugs 41, 42. The other end of the lever 38 is hollowed out at 43 to hold the foot pin 44, which extends through the floor of the platform within convenient reach of 30 the motorman, so that by stepping on the pin contact is made between the bolts 37 and 40 and the contact plate 36 is brought into the 35 circuit. As soon as the motorman releases the foot pin 44 the switch points separate 40 by gravity. One of these switches and its connection is provided for each end of the car.

In the ordinary running of the car, the contact plate 36 is disconnected, but as the 45 car approaches the switch point and the motorman desires to operate the same, to run off on the branch track, he depresses the

foot pin 44 and as soon as contact is made through the plate 36, with the contact box cover 31, the circuit is completed through 50 the solenoid to draw over the core and thus shift the switch point to open the branch line. As the car passes on to the branch line, the motorman again depresses the foot pin and the contact plate coming in contact with 55 the box the circuit is completed to actuate the solenoid to draw back the core and thus shift the switch point back to normal.

There is nothing in the construction above described that can get out of order or cause 60 trouble. The contact boxes form no obstruction in the street, and they cannot be damaged or gotten out of order by the street traffic. The actuating solenoid is thoroughly 65 water-proof and even if the box holding the solenoid should become full of water, the solenoid will still operate. The solenoid core is connected directly to the switch point, and there are no pivoted levers or gearing of any kind to get out of order. The contact plate 70 in the car is only brought into circuit when the motorman presses the foot pin, and the entire construction can be readily and easily installed without any difficulty whatever.

Having thus described my invention what 75 I claim as new and desire to secure by Letters Patent, is:

In a device of the character specified, a contact box to be located in the roadway comprising a metal box with a central brace 80 extending between the sides, a beveled metal lid with insulating material between the lid and sides of the box, and a central screw for securing the lid to the box brace with insulation between the screw and brace and a 85 pivoted switch point and solenoid to operate same with connection between the contact box screw and the solenoid coils whereby the solenoid may be energized through the contact box.

FRANKLIN RICE.
